UNITED STATES PATENT OFFICE.

KARL D. SMITH, OF BATTLE CREEK, MICHIGAN, ASSIGNOR TO UNION STEAM PUMP COMPANY, OF BATTLE CREEK, MICHIGAN.

EMULSIFYING-MACHINE.

1,316,115.

Specification of Letters Patent. Patented Sept. 16, 1919.

Application filed May 19, 1919. Serial No. 298,283.

To all whom it may concern:

Be it known that I, KARL D. SMITH, a citizen of the United States, residing at Battle Creek, county of Calhoun, State of Michigan, have invented certain new and useful Improvements in Emulsifying Machines, of which the following is a specification.

This invention relates to improvements in emulsifying machines.

My improvements as herein illustrated are particularly designed by me for treating milk or cream or mixing butter or fat with milk or cream, although desirable for use in emulsifying or mixing other substances.

The main object of my invention is to provide an improved device of the class described in which accurate and fine adjustments are possible and easily accomplished.

20 Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is an elevation of a structure embodying the features of my invention.

Fig. II is a detail view mainly in central vertical section.

Fig. III is a bottom view.

Fig. IV is a cross section on a line corresponding to line 4—4 of Fig. II.

In the drawing, similar reference characters refer to similar parts throughout the several views.

Referring to the drawing, I provide a body or casing 1 having a chamber 2 therein and a bore 3. At the lower end of the bore 3 is an inlet 4 to which the lateral inlet 45 or supply pipe 5 is connected.

The chamber 2 is provided with a lateral discharge 6. The conical valve member seat 7 faces into the chamber, the bore 3 being central of this valve member seat. The 50 valve member 8 is conical to correspond to this seat, and is provided with a stem 9 extending through the bore 3 and projecting through an opening 10 in the bottom of the casing, so that the end of the stem is exposed.

A packing 11 is provided for the stem below the inlet 4, the packing gland 12 being secured to the end of the casing by the tap screws 13. The portion 14 of the stem fitting the bore 3 is cut away at 15 to provide 60 passages from the inlet 4 to the valve seat, there being a distributing groove 16 just below the valve member 8, so that the liquid is uniformly distributed to the valve member seat from these passages, there being four of 65 them in the structure illustrated. The valve member 8 is retained upon the stem by the clamping nut 17.

The movement of the valve member from its seat is determined and the valve is fixedly 70 supported when under pressure by an adjusting means comprising in the structure illustrated the members 18, 19, and 20. The member 18 is a bushing-like casing member threaded into the casing and internally 75 threaded to receive the outer member 19, which is internally threaded to receive the member 20. The member 19 is provided with an adjusting hand wheel 21.

The inner member 20 engages the valve 80 constituting in effect a thrust member therefor. The member 20 is held against rotation by the lugs or lateral portions 22 thereon which coact with lugs 23 on the member 18. The threads of the members 19 and 20 85 are of different pitch, no effort being made to accurately illustrate the difference in pitch, as it will be understood that the purpose is to secure a very fine and accurate adjustment for the valve, and also a powerful 90 means of adjustment which enables this fine and accurate adjustment of the valve while under high pressure.

The extension of the stem 9 through the casing, however, and the delivery of the fluid 95 under pressure through the inlet 4, against the side instead of against the end of the valve stem, very materially reduces the end thrust and consequently the strains on the parts and power necessary to adjust the 100 valve while under pressure. As these machines are operated under high pressure, sometimes running into thousands of pounds per square inch, the advantage of this reduction of end thrust is apparent.

105 I have illustrated and described my improvements as I have embodied the same in one form. I have not attempted to illustrate or describe other adaptations or modifications, as I believe the disclosure made will 110

enable those skilled in the art to which my invention relates to embody or adapt the same as may be desired.

Having thus described my invention, what I claim as new and desire to secure by Letters Patent is:

1. In a structure of the class described, the combination with a casing having a valve member chamber, an upwardly facing 10 valve member seat, a bore centrally of said seat, a lateral connection at the lower end of said bore, and a lateral discharge connection above said valve seat, a valve member coacting with said seat provided with a stem 15 disposed through and guided by said bore and projecting through the end of the casing, said stem having cutaway portions within said bore providing passages from the inlet to the valve seat, a packing for the projecting end of said stem disposed below said inlet, a means for fixedly supporting said valve member comprising a pair of adjusting 20 members, the inner of which engages the valve member and has threaded engagement with the outer, and is provided with laterally projecting lugs, and a bushing-like casing member into which the outer adjusting member is threaded provided with parts coacting with said lugs to support the inner 25 adjusting member against rotation, said outer adjusting member being provided with an 30 adjusting handle.

2. In a structure of the class described, the combination with a casing having a valve 35 member chamber, an upwardly facing valve member seat, a bore centrally of said seat, a lateral connection at the lower end of said bore, and a lateral discharge connection above said valve seat, a valve member coact- 40 ing with said seat provided with a stem disposed through and guided by said bore and projecting through the end of the casing, said stem having cutaway portions within said bore providing passages from the inlet 45 to the valve seat; a packing for the projecting end of said stem disposed below said inlet, a means for fixedly supporting said valve member comprising a pair of adjusting members, the inner of which engages the 50 valve member and has threaded engagement with the outer, the outer having threaded connections with the casing.

3. In a structure of the class described, the combination with a casing having a valve 55 member chamber, an inwardly facing valve member seat, a bore centrally of said seat, a lateral connection at the lower end of said bore, and a lateral discharge connection above said valve seat, a valve member coact- 60 ing with said seat provided with a stem disposed through and guided by said bore, and projecting through the end of the casing, said stem having cutaway portions within

said bore providing passages from the inlet to the valve seat, a packing for the projecting end of said stem disposed below said inlet, and a screw means for fixedly supporting said valve member.

4. In a structure of the class described, the combination with a casing having a lateral inlet and outlet and a valve seat member seat between said inlet and outlet, and a bore centrally of said valve member seat, and into which the inlet opens, a valve member coacting with said seat provided with a stem disposed through said bore and projecting through the end of the casing, a packing for the projecting end of said stem, a means for fixedly supporting said valve member comprising a pair of adjusting means, the inner of which engages the valve member and has threaded engagement with the outer, and is provided with laterally projecting lugs and a bushing-like casing member into which the outer adjusting member is threaded provided with parts coacting with said lugs to support the inner adjusting member against rotation, said outer adjusting member being provided with an adjusting handle.

5. In a structure of the class described, the combination with a casing having a lateral inlet and outlet and a valve seat member seat between said inlet and outlet, and a bore centrally of said valve member seat, and into which the inlet opens, a valve member coacting with said seat provided with a stem disposed through said bore and projecting through the end of the casing, a packing for the projecting end of said stem, a means for fixedly supporting said valve member comprising a pair of adjusting means, the inner of which engages the valve member and has threaded engagement with the outer, the outer having threaded connections with the casing.

6. In a structure of the class described, the combination with a casing having a lateral inlet and outlet and a valve seat member seat between said inlet and outlet, and a bore centrally of said valve member seat, and into which the inlet opens, a valve member coacting with said seat provided with a stem disposed through said bore and projecting through the end of the casing, a packing for the projecting end of said stem, and a means for fixedly supporting said valve member.

In witness whereof, I have hereunto set my hand and seal in the presence of two 120 witnesses.

KARL D. SMITH. [L. S.]
